WRECKING BAR

Robert E. Lee, North Branch, Minn.

Application July 7, 1950, Serial No. 11,001

Term of patent 7 years

(Cl. D54—13)

To all whom it may concern:

Be it known that I, Robert E. Lee, a citizen of the United States of America, residing at North Branch, in the county of Chisago and State of Minnesota, have invented a new, original, and ornamental Design for a Wrecking Bar, of which the following is a specification, reference being had to the accompanying drawing, forming a part thereof.

In the drawing:

Fig. 1 is a rear elevational view of a wrecking bar showing my new design.

Fig. 2 is a side elevational view of Fig. 1.

Fig. 3 is a front elevational view of Fig. 1.

Fig. 4 is a perspective view of my wrecking bar.

I claim:

The ornamental design for a wrecking bar, as shown.

ROBERT E. LEE.
